UNITED STATES PATENT OFFICE

2,536,405

LAND LEVELER WITH COORDINATED
WHEEL ADJUSTMENT MEANSClyde Whittier, Monte Vista, Colo., assignor of
one-half to H. E. Schall, Monte Vista, Colo.

Application November 28, 1947, Serial No. 788,337

3 Claims. (Cl. 37—180)

1

This invention relates to a land leveling device, and has for its principal object the provision of a leveler which will have an exceedingly long leveling blade so that swaths over one hundred feet in length can be leveled at one time. This great width serves a double purpose: first, it speeds up the operation of leveling large land areas; second, the greater the width of the blade, the more perfectly the leveling can be done, since all of the area within the blade width can be brought to a perfect level simultaneously.

Another object of the invention is to provide a land leveler of great width which will not bow or bend in any direction throughout its length.

A still further object is to provide an accurate, easily and centrally controlled mechanism for bringing the leveling blade into exact adjustment both for level operation and depth of cut.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a plan view of the improved leveling device;

Fig. 2 is a side view of the leveling blade and drawbar attachment;

Fig. 3 is a cross-section, taken on the line 3—3, Fig. 1;

Fig. 4 is a front view of the improved leveling device;

Fig. 5 is a cross-sectional view taken on the line 5—5, Fig. 1; and

Fig. 6 is an end view of the improved land leveling device.

The main frame of the leveler is formed of tubing and consists of three longitudinal truss tubes, an upper truss tube 10, a lower truss tube 11, and a rear truss tube 12. The lower truss tube 11 is perfectly straight. The three tubes 10, 11, and 12 join at the extremities of the device and separate from each other as the middle of the leveler is approached so as to form the outlines of a triangular truss structure. The truss structure is completed by front truss struts 13, upper truss struts 14, and lower truss struts 15. This construction provides an exceedingly

2

rigid structure, since all of the truss members resist bending in all directions.

A curved scraper blade 16 is fixedly mounted along the front face of the lower truss tube 11. The scraper blade and the truss structure are supported above the ground by means of a pair of front wheels 17 and two pairs of rear wheels 18.

The front wheels are mounted on a caster dolly 19 which is mounted on the lower extremity of a vertical pivot shaft 45. The shaft 45 is rotatably mounted in a pivot tube 20. The pivot tube 20 is rigidly connected with the upper and lower truss tubes 10 and 11 by means of a forward truss bracket 21. The pivot tube 20 can be raised and lowered with reference to the caster dolly 19 by means of a threaded jack shaft 22 operated from a hand wheel 23. The jack shaft is threaded through a cap nut 44 fixed to the top of the tube 20. The lower extremity of the jack screw bears against the upper extremity of the pivot shaft 45.

The pairs of rear wheels 18 are mounted in caster brackets 24 which are mounted on the lower extremities of pivot shafts 25. The pivot shafts are vertically slidable and rotatable within vertical guide tubes 26. The guide tubes are rigidly supported in a vertical position by means of rear bracket trusses 27 from the upper truss tube 10 and the rear truss tube 12.

The tubes 26 can be lifted on the pivot shafts 25 by means of a cable 28. The extremities of the cable 28 are attached to the two guide tubes 26, as shown at 29. From each attachment, the cable passes over a post sheave 30, there being one of the sheaves 30 in the top of each of the shafts 25. From each sheave 30, the cable 28 passes downwardly under a guide sheave 31, there being one guide sheave mounted on each of the guide tubes 26. From each guide sheave 31, the cable passes over an idler sheave 32, thence around a winch drum 33 mounted on a platform 34 at the middle of the leveler. The winch drum can be rotated by hand by means of a hand wheel 35.

It can be seen that if the hand wheel 35 is rotated in one direction, it will let out the cable to one of the shafts 25 and take in the cable to the other of the shafts 25, so that the opposite ends of the triangular truss can be raised and lowered alternately. The pairs of rear wheels 18 are positioned adjacent the outer extremities of the triangular truss frame, and the pair of front wheels 17 is placed adjacent the middle of the truss frame. This causes the front wheels to act as a tilting fulcrum to allow the blade 16 to be tilted up and down at its extremities.

The improved leveler is designed to be drawn by two towing vehicles, such as "Caterpillar" tractors or the like. The towing vehicles are attached to the leveler by means of swinging draw bars 36, terminating at their forward extremities in tractor hitch links 37. The rear extremity of each draw bar 36 is mounted on a hinge pin 38 carried by hinge ears secured on a rotatable tube 39 surrounding a vertical pivot shaft 40. The pivot shafts 40 are mounted in brackets 41 extending from the upper and lower truss tubes 10 and 11, respectively.

The draw bars are positioned on each side of the center and adjacent the extremities of the leveler and are supported from the tubes 39 by means of adjustable bracket arms 42. The lower extremities of the bracket arms can be attached in any desired one of a series of adjustment holes 43 to vary the height of the draw bars 36. This allows the draw bars to be adjusted in height to suit the particular towing vehicle, and also allows them to swing laterally with the sideward movements of the towing vehicle.

In use, the height of the scraper blade 16 is pre-set by means of the hand wheel 23. The level or pitch of the blade is pre-set by means of the hand wheel 35. The device is then drawn over the land by the two towing vehicles through the medium of the draw bars 36.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. A land leveler comprising: an elongated laterally extending trussed frame; a relatively long, straight scraper blade permanently secured along the lower front edge of the truss frame; a front wheel bracket extending forwardly from the middle of said truss frame; a rear wheel bracket extending rearwardly from adjacent each extremity of said truss frame; front caster wheels rotatably mounted on said front wheel bracket; a vertical guide tube carried by each of said rear wheel brackets; a vertical pivot post rotatably mounted in and extending downwardly from each of said guide tubes; a caster dolly on the lower extremity of each pivot post; ground-engaging wheels mounted on said caster dollies; and means for oppositely raising and lowering said guide tubes on said pivot posts so as to simultaneously raise one end of said blade and lower the other end thereof, said front wheels acting as a tilting fulcrum.

2. A land leveling machine comprising: an elongated truss frame; a scraper blade mounted on and extending downwardly from said frame throughout its length; a front wheel bracket extending forwardly from the middle of said frame; a rear wheel bracket extending rearwardly from

5 adjacent each extremity of said frame; front caster wheels supporting said front wheel bracket; vertical pivot tubes carried by said rear wheel brackets rearwardly of said blade; pivot shafts extending vertically through said tubes; rear caster wheels mounted on the lower extremities of said pivot shafts, said pivot shafts extending upwardly and downwardly from said guide tubes; a cable sheave mounted on the upper extremity of each pivot shaft; a winch drum mounted on said truss frame; and a cable extending from each guide tube over the sheave of that pivot shaft and around said winch drum so that rotation of said drum will simultaneously raise one guide tube and lower the other.

3. A land leveling machine comprising: an elongated truss frame; a scraper blade mounted on and extending downwardly from said frame throughout its length; a front wheel bracket extending forwardly from the middle of said frame; a rear wheel bracket extending rearwardly from adjacent each extremity of said frame; front caster wheels supporting said front wheel bracket; vertical pivot tubes carried by said rear wheel brackets rearwardly of said blade; pivot shafts extending vertically through said tubes; rear caster wheels mounted on the lower extremities of said pivot shafts, said pivot shafts extending upwardly and downwardly from said guide tubes; a cable sheave mounted on the upper extremity of each pivot shaft; a winch drum mounted on said truss frame; a cable extending from each guide tube over the sheave of that pivot shaft and around said winch drum so that rotation of said drum will simultaneously raise one guide tube and lower the other; and a threaded jack shaft carried by said front wheel bracket and arranged to raise and lower the front wheel bracket with reference to said front wheels.
